UNITED STATES PATENT OFFICE.

CLEMENS G. BODUNGEN, OF LAGRANGE, TEXAS.

COTTON-GIN.

SPECIFICATION forming part of Letters Patent No. 772,272, dated October 11, 1904.

Application filed March 16, 1904. Serial No. 198,421. (No model.)

To all whom it may concern:

Be it known that I, CLEMENS G. BODUNGEN, a citizen of the United States, residing at La-
5 grange, in the county of Fayette and State of Texas, have invented a new and useful Im-
provement in Cotton-Gins, of which the fol-
lowing is a specification.

My present invention relates to an improve-
ment in cotton-gins, and more particularly to
10 the gearing whereby motion is transmitted
from the saw-shaft to the brush-shaft of the
gin. In those gin constructions with which I
am familiar a series of gin-saws are mounted
on a saw-shaft driven by the application of
15 power thereto and arranged in turn to drive,
through the medium of a belt, a brush-shaft
carrying a brush or a series of brushes oper-
ating in proximity to the saws. Many valid
objections may be urged against this arrange-
20 ment, particularly the transmission of power
from one shaft to another by means of a belt,
the most prominent of such objections being
the excessive vibration of the parts, the tor-
sional strains on the brush-shaft, the friction
25 induced in the bearings of such shaft by its
tendency to endwise movement, and the fre-
quent necessity for slackening or tightening the
brush-shaft and for applying resin or other
frictional substance to the engaging surfaces
30 of the belt and pulleys. Having in mind these
objectionable characteristics of the usual ar-
rangement for transmitting motion from one
shaft to the other, the object of my invention
is to produce a simple and inexpensive form
35 of motion-transmitting mechanism between
the saw and brush shafts of the gin, by the use
of which the parts will be made to run
smoothly without vibration, without undue
torsional strain on the brush-shaft, and with-
40 out tendency to endwise movement of the shaft
or undue friction in the bearings thereof.

To the accomplishment of the recited ob-
jects and others subordinate thereto the in-
45 vention resides in that construction and ar-
rangement of parts to be hereinafter de-
scribed, illustrated in the accompanying draw-
ings, and defined in the appended claim.

In said drawings, Figure 1 is a plan view of
a gin-stand equipped in accordance with my
50 invention. Fig. 2 is a detail sectional view, on

a somewhat enlarged scale, of the gearing at
one side of the gin. Fig. 3 is a face view of
the gearing, and Fig. 4 is a detail view of one
of the small friction-wheels.

Like numerals of reference are employed to 55
designate corresponding parts throughout the
several views.

1 indicates a gin-stand of ordinary construc-
tion; 2, the breast; 3, the gin-saws, and 4 the
brush. The gin-saws 3 are mounted, as usual, 60
on a saw-shaft 5, journaled at each end there-
of in a pair of bearing-boxes 6 and 7, mounted
on the frame, as shown. The brush 4 is
disposed parallel with the gang of gin-saws
to clear the same and is carried by a brush- 65
shaft 8, parallel with the saw-shaft 5 and like-
wise provided beyond each end of the brush
with bearing-boxes 9 and 10. As is usual
in this class of machines, power is applied to
the saw-shaft 5 to rotate the saws, said shaft 70
being equipped with a belt-pulley 11 for the
application of a power-belt. (Not shown.)

In accordance with my invention motion is
transmitted to the brush-shaft 8 from the saw-
shaft 5 by gearing arranged in a novel man- 75
ner to eliminate the objections to the usual
brush-belt ordinarily employed in this con-
nection. As shown in Fig. 1 of the draw-
ings, the shaft 5 is equipped with a pair of
oppositely-disposed beveled friction-wheels 80
12 and 13, each adjustably retained upon the
shaft by set-screws 13^a between the bearing-
boxes of each pair. The wheels 12 and 13
are disposed to frictionally engage a pair of
somewhat smaller beveled friction-wheels 85
14 and 15, mounted on the brush-shaft 8 and op-
positely disposed with respect to each other
and also with respect to the larger wheels en-
gaged thereby. This particular relation of
the wheels is material. It will be noted that 90
the outer or back faces of the wheels 12 and
13 are those of greatest diameter, while the
outer faces of the small wheels 14 and 15 are
those of least diameter. It follows, there-
fore, that any end thrust of the brush-shaft 95
in either direction is sustained by the larger
wheels, which thus constitute means resisting
endwise movement of the brush-shaft in either
direction. Ordinarily the tendency of the
brush-shaft to endwise movement induces 100

the outer or back faces of the wheels 12 and
13 are those of greatest diameter, while the
outer faces of the small wheels 14 and 15 are
those of least diameter. It follows, there-
fore, that any end thrust of the brush-shaft 95
in either direction is sustained by the larger
wheels, which thus constitute means resisting
endwise movement of the brush-shaft in either
direction. Ordinarily the tendency of the
brush-shaft to endwise movement induces 100

- undue friction in the bearings of such shaft, while, on the contrary, in the described arrangement this end thrust merely serves to increase the frictional contact of the driving 5 and driven wheels and renders more positive the transmission of motion. It will be seen, furthermore, that motion is positively transmitted to both ends of the brush-shaft, so that the torsional strains and the objectionable vibration 10 ordinarily incident thereto is wholly eliminated, while at the same time the brush is rotated smoothly and easily in a direction opposite to the rotation of the saws and at a somewhat higher speed.
- 15 It has been stated that the larger wheels 12 and 13 are adjustable upon the saw-shaft, and it will be seen that this adjustability makes it possible to take up wear and to insure at all times an effective frictional contact between 20 the driving and driven wheels without material loss of time in the operation of the gin.
- While the specific character of friction-wheels aside from their relative arrangement is immaterial so far as the broader aspect of 25 the invention is concerned, I nevertheless prefer to construct these elements substantially as shown in Fig. 2. In this figure the wheel 12 is shown to be a light metal casting having its beveled periphery formed by a 30 trunko-conical flange 16 and provided with a hub 17, fitted upon the saw-shaft and carrying the set-screws 13^a, the inner ends of which preferably engage depressions or recesses 18 in the shaft. The small friction-wheel 14 instead of being formed in a single casting is 35 preferably composed of a pair of circular face-plates 19 and 20, connected by bolts 21, which pass through a series of leather, rawhide, or other suitable disks 22 of gradually-diminishing 40 diameter to form a trunko-conical or beveled engaging face opposed to the beveled periphery of the wheel 12. It should be observed in this connection that the largest leather disk 22 is of greater diameter than the 45 face-plate 20, so that the wheel 12 is not permitted to contact with any metal part of the

wheel 14, but engages exclusively a comparatively yielding frictional material interposed between the face-plates thereof.

If desired, the smaller wheels 14 may be 50 adjustable on the brush-shaft, and the face-plates 20 are therefore provided with hubs 23, carrying set-screws 24, engaging the brush-shaft 8, as shown. It will of course be understood that the wheels at both sides of the 55 gin are similarly constructed and arranged.

It is thought that from the foregoing the construction, operation, and many advantages of my invention will be readily apparent without further description; but while the present 60 embodiment of the invention is believed at this time to be preferable I do not desire to limit myself to the structural details defined, as, on the contrary, I reserve the right to effect such changes, modifications, and variations thereof as may fall fairly within the scope 65 of the protection prayed.

What I claim is—

In a cotton-gin, the combination with a gin-stand, a saw-shaft and saws and a brush-shaft 70 and brush, of a pair of bearings for each end of the saw-shaft, a pair of oppositely-disposed beveled friction-wheels adjustably mounted on the saw-shaft and each located between the bearings at one end of the shaft, a pair of bearings for each end of the brush-shaft, and a pair of comparatively small beveled friction-wheels mounted on the brush-shaft and engaging the wheels on the saw-shaft, each of 75 the smaller wheels being located between a pair of bearings at one end of the brush-shaft and consisting of connected face-plates and 80 intermediate laminated frictional material engaged by a wheel on the saw-shaft.

In testimony that I claim the foregoing as 85 my own I have hereto affixed my signature in the presence of two witnesses.

CLEMENS G. BODUNGEN.
